SHOE

Richard Jerro, New York, N. Y., assignor to Jerro Brothers, New York, N. Y., a copartnership

Application January 13, 1941, Serial No. 374,196

1 Claim. (Cl. 36—8.5)

My invention relates to a novel shoe construction and more particularly relates to a novel combination of shoe shank and upper adapted to be used in women's shoes in which the shank is so shaped and positioned with relation to the upper that the wearer's foot rests not only on the rigid shank, but the sides of the foot also rest upon and are embraced by the lower portion of the shoe upper thereby obtaining a glove-like fit of the upper about the foot.

In women's shoes foot comfort and shoe fit is often subservient to shoe style. Because of the high heels employed and the design of the shoes, it is necessary that a rigid shoe shank be employed for the support of the arch. This rigid shank, although serving to support the foot is to a certain extent uncomfortable.

The keystone of the arch is the cuboid bone. The surrounding bones of the arch and metatarsal namely the astragalus, scaphoid and cuneiform bones, all depend upon the supporting effect of the cuboid bone. In order to obtain proper support for the foot, it is necessary that the cuboid bone be maintained in proper position and that the adjacent bones be also held in their proper and respective position relative to the cuboid.

I have found that by causing the arch of the foot to be supported in part and to be embraced by the shoe upper, I can obtain a more scientifically improved shoe and a more comfortable support for the foot, especially the arch thereof. I have further found that by causing the upper to be so positioned with relation to the shank, that the foot rests partially upon the upper and is closely gripped thereby, that a better fit of the upper about the foot is also obtained. The aforesaid arrangement eliminates gapping, buckling and looseness and furthermore eliminates the bulges in the shoe upper that ordinarily occur with the use of ordinary upper while the wearer of the shoe is in the act of walking.

My invention primarily is accomplished by employing a shank that is of lesser width in the long arch area than the ordinary shank and by bringing the upper out and away from the shank in such a manner that the wearer's foot rests in part on the shank and on the sides rests on the upper, the upper being caused to be fitted about the foot so that it closely embraces the same.

To obtain the foregoing effect the upper at the uppermost edge thereof is closely stitched and relatively non-elastic, but at the lower region thereof in the area where it is adjacent the shank, the upper is relatively elastic and has a certain amount of "give."

It is the object of my invention to provide a novel combination of shank and upper.

It is a further object of my invention to provide a shoe having a shank that is cut in deeper

at the sides than has hitherto been the practice in the art.

It is a further object of my invention to provide a shank, deeply cut in at the sides so that the upper combined therewith is adapted to support the sides of the foot resting on the shank.

It is a further object of my invention to provide a novel combination of shank and upper so that the shoe drapes around the foot from the bottom to the sides to obtain a close glove fit of the upper on the foot.

It is a further object of my invention to provide a non-gapping, non-bulging shoe by the herein described combination of particular shank and upper. In the further description of my invention, reference is had to the drawing in which:

Fig. 1 is a perspective view of a shoe embodying the invention on a foot, with part of the shoe broken away and in cross-section;

Fig. 2 is a side elevational view of the improved shoe on a foot;

Fig. 3 is a view similar to Fig. 2, but showing the position of the shoe when the person wearing the same stands up on the toe;

Fig. 4 is a top plan view of a shoe embodying the invention;

Fig. 5 is a cross-sectional view taken on line 5—5 of Fig. 2; and

Fig. 6 is a cross-sectional view similar to Fig. 5, of a standard shoe having a shank of normal width showing the arch of the foot supported on the hard shank and not on the soft upper leather, as in Fig. 5.

Referring now more specifically to the drawing, in Fig. 1 there is shown a shoe 10 on a wearer's foot 11. The shoe 10 comprises a sole and an upper attached thereto. The upper is shown in the drawing as an open back, and is provided with a rearwardly extending strap which is adapted to embrace the upper portion of the heel of the foot 11.

As shown in the drawing, the shank portion 16 of the sole between the heel portion thereof and the ball portion of the sole, is cut narrow on opposite sides of the medial line of the sole producing a shank of narrowed width. The shank 16 is narrower than shanks for standard soles of similar size and the decrease in the width of the shank is not only on one side of the medial line of the sole, but on both sides thereof. Thus, the upper of the shoe is shown in Fig. 1 of the drawing for the purpose of illustration, as broken away at 18, whereby to show that at the bottom area 14 thereon on one side of the shank of the sole, the shoe upper curves downwardly and under the foot 11 to support a portion of the underside of the foot on one side of the shank. Likewise the bottom portion of the upper on the other side of the narrow shank also curves down-

wardly under the foot to support the underside of the foot on the opposite side of said shank.

The dotted line 15 in Fig. 1 indicates the line of the shank of the shoe, and it will be noted that the shank is inwardly spaced from the margin of the underside of the foot so that side portions of the underside of the foot 11 rest on portions of the upper adjacent the shank and on opposite sides of said shank.

In Figure 5 which shows in part a section along the line 5-5 of Figure 2, it will be seen that the shank 16 of the shoe 10 is cut particularly deeply at the side areas 17 and 18 and this deep cut effect is an important feature of my invention in that it insures that the foot will rest upon the soft and yielding portion 14 and 20 of the upper when the shoe is worn. Diagrammatically here the upper is shown positioned between the shank 16 and the outsole 21. Thus, the shank is of narrower width than standard shanks for the same size shoe, but has the same longitudinal medial line since the edges 17 and 18 are closer to said medial line than in standard shoes.

Figure 5 represents the positioning of the various parts of the shoe of my invention when a foot is placed within the shoe. The foot 11 shown in dotted line rests centrally upon the shank 16 and at the sides rests upon the portion 14 of the upper and the portion 20 of the upper. The area 14 is beneath the inside of the foot namely the portion of the foot adjacent the long arch and this long arch area of the foot rests on the area 14 of the upper.

Because the sides of the foot rest upon the soft and resilient upper instead of the non-resilient and non-yielding shank 16, greater foot comfort results, and particularly a closer glove-like fit is obtained since in the act of walking the pressure of the foot downwardly upon the upper at 14 and 20 causes, for example, the back strap 25, shown in Figure 2, of the shoe to more closely hug the heel. This elimination of the normal bulging or buckling of the shoe upper in the act of walking is of great importance since this relative movement of the upper during walking is responsible for blisters and foot discomfort as well as inferior appearance.

In Figure 4 which is a plan view of the shoe, it will be noted that the deeply cut shank and the adjacent upper affords a partially rigid and partially resilient support for the foot. Specifically I have found that if I form the shank so that it is approximately $\frac{1}{8}$ of an inch less in width on both sides in contrast to the normal standard shank of commerce for similar size shoe, then I can obtain the desired results here set forth.

The shank is cut deeply not only where the arch area joins the heel as at 30 and 31, but also at the fore part or adjacent the ball area of the foot at 32 and 33.

In Figure 6 it will be noted that in the ordinary shoe, the foot 40 rests entirely upon and is supported by the rigid unyielding shank 41 and the upper 42 and 43 serves only to hold the foot in at the sides.

In contrast to the yielding resilient support and the glove like fit shown in Figure 3, the foot here is loosely encompassed by the upper and upon movement can obviously cause buckling and wrinkling.

The heel area 50 (see Figure 2) is sufficient in area to afford full and complete support for

the heel of the wearer's foot. The principle of employing a resilient support of the upper applies only to the long arch area of the shoe of my invention and not to the heel area.

Further, if the arch is improperly supported and the foot health may suffer by the dislocation of the cuboid and adjacent scaphoid bones.

Accordingly, I provide a novel shoe construction in which the shank is so cut and joined to the upper that the foot rests centrally upon the shank and at the sides upon the upper and is supported thereby, the upper thereby being caused to fit closely about the foot.

Although I have specifically pointed out that the shank should be cut in approximately $\frac{1}{8}$ of an inch on each side more than the normal shank of commerce, it is to be understood that this can vary slightly and my invention is directed to the principles hereinbefore set forth.

The present invention and novel construction of shoe shank and shoe upper is directed both to improving foot health and improving shoe appearance. It is an established fact that for increased foot comfort and foot health it is desirable that the various bones of the longitudinal or long arch, namely the keystone cuboid bone and the adjacent scaphoid, cuneiform and astragalus bones have a restricted amount of play so that the muscles and tendons which join the various bones will retain or regain their desirable muscle tone. A limited movement of these parts promotes better circulation and releases cramped nerves and blood vessels. However, it is desirable that this relative movement be restricted so that there will be no strain on the part and no consequent weakening. By providing the additional resilient support for this long or longitudinal arch area of the foot by means of this newly described locationing of the upper, the proper and extremely desirable resilient gripping of the arch and the various bones is afforded.

From the standpoint of appearance and style, this proper gripping of the longitudinal arch area of the foot, obviates sagging and spreading often found and more particularly because of the glove-like fit and resilient embrace of the foot by the upper, the gapping and buckling of the upper with respect to the foot is obviated.

Although my invention is here described and illustrated with respect to a shoe having a back strap because the problems of gapping and buckling are of particular importance in this type of shoe, my invention is applicable to shoes of other types and is so intended.

I claim:

A shoe comprising a shank, an upper attached thereto and extending from the sides thereof, said upper being formed with an open back and provided with a strap adapted to engage the back of the wearer's foot, said shank being substantially narrower than shanks of standard shoes of similar size, while having substantially the same medial line as shanks of standard shoes of similar size, and portions of the upper on opposite sides of said shank underlying the undersides of the wearer's foot on opposite sides of the shank, whereby to resiliently support said side portions of the foot, and also to pull the strap against the back of the wearer's foot, when the foot in the shoe is raised up on its toe to prevent gap between the strap and the back of the foot.

RICHARD JERRO.
